[57] CLAIM

The ornamental design for a cockpit type game machine, as shown and described.

DESCRIPTION

FIG. 1 is a front elevational view of the cockpit type game machine showing my new design;

FIG. 2 is a rear elevational view;

FIG. 3 is a right-hand side elevational view;

FIG. 4 is a top plan view;

FIG. 5 is a bottom plan view;

FIG. 6 is a perspective view; and

FIG. 7 is a perspective view from the opposite side of FIG. 6.

The left-hand side view is a reversed, but otherwise identical, view to that seen in FIG. 3.

FIG. 1

FIG. 3

FIG. 2

FIG. 4

FIG. 5

FIG. 6
